(57) **CLAIM**

The ornamental design for a mop head, as shown and described.

DESCRIPTION

FIG. 1 is a first perspective view of a mop head showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2;

FIG. 11 is an enlarged view of the selected portion 11 in FIG. 5;

FIG. 12 is an enlarged view of the selected portion 12 in FIG. 7; and,

FIG. 13 is an enlarged view of the selected portion 13 in FIG. 8.

The dot-dash broken lines in FIGS. 1, 2, 5, 7, 8, 9, 10, 11, 12 & 13 are used to show an area of enlargement and with the broken lines forming no part of the claimed design.
